UNITED STATES PATENT OFFICE.

ELLA K. PILLING, OF PHILADELPHIA, PENNSYLVANIA.

DESIGN FOR A WAIST-LENGTHENER.

SPECIFICATION forming part of Design No. 34,768, dated July 9, 1901.

Application filed June 4, 1901. Serial No. 63,166. Term of patent 7 years.

To all whom it may concern:

Be it known that I, ELLA K. PILLING, a citizen of the United States, residing at the city of Philadelphia, in the county of Philadelphia and State of Pennsylvania, have invented and produced a new and original Design for Waist-Lengtheners, of which the following is a specification, reference being had to the accompanying drawings, forming part hereof, in which—

Figure 1 is a top or plan view of a waist-lengthener, illustrating my new design; and Fig. 2 is an edge view thereof.

As illustrated in the drawings, the leading or material features of my design consist in the particular configuration or outline of the waist-lengthener and the surface ornamentation thereof. When viewed in plan, as illustrated in Fig. 1, the design consists of an intermediate narrow portion *a*, merging at each end into an irregular triangular-shaped enlargement *b*, the end *b'* of which is inclined and meets the lower edge of the lengthener

in a point *b*³. The intermediate narrow portion *a* is ornamented with a series of circular ornaments *a'*, arranged in two courses. The triangular or pointed ends *b* are ornamented with ribs *b*³, radiating or fan-shaped in plan. These ribs *b*³, as clearly illustrated in Fig. 2, project above the two surfaces of the lengthener. The inclined edge *b'* of the ends *b* are further ornamented by a row of circular ornaments *b*⁴.

Having thus described my invention, what I claim as new, and desire to secure by Letters Patent, is—

The design for a waist-lengthener, as shown and herein described.

In testimony whereof I have hereunto set my signature in the presence of two subscribing witnesses.

ELLA K. PILLING.

Witnesses:

J. WALTER DOUGLASS,
THOMAS M. SMITH.
